(57) **CLAIM**

The ornamental design of a sipping lid for a beverage holder, as shown and described.

DESCRIPTION

FIG. 1 is an elevation of our sipping lid for a beverage holder design as seen from one side thereof;

FIG. 2 is an elevation of our sipping lid for a beverage holder design taken from the right of FIG. 1;

FIG. 3 is an elevation of our sipping lid for a beverage holder design taken from the left of FIG. 1;

FIG. 4 is a top view of our sipping lid for a beverage holder design;

FIG. 5 is a bottom view of our sipping lid for a beverage holder lid design; and,

FIG. 6 is a vertical section of our sipping lid for a beverage holder lid design, taken along the line 6—6 in FIG. 4.

It is to be understood that a rear view of our sipping lid for a beverage holder design is a mere image of FIG. 1.
